UNITED STATES PATENT OFFICE.

JARET W. DENTON, OF HENDERSON, KENTUCKY.

SCRAPING AND GRADING MACHINE.

SPECIFICATION forming part of Letters Patent No. 448,415, dated March 17, 1891.

Application filed June 21, 1890. Serial No. 356,273. (No model.)

To all whom it may concern:

Be it known that I, JARET W. DENTON, a citizen of the United States, residing at Henderson, in the county of Henderson and State 5 of Kentucky, have invented a new and useful Scraping and Grading Machine, of which the following is a specification.

This invention has relation to scraping and grading machines; and the objects of the invention are to increase the capacity of the machine without correspondingly increasing the necessary power for operating the same, and to provide withal a cheap and simple construction adapted to take up the dirt in convenient quantities, transport the same to a desired point, and simultaneously dump all of the scrapers or shovels.

Other objects and advantages of the invention, together with the novel features thereof, will appear in the following description and be particularly pointed out in the claims.

Referring to the drawings, Figure 1 is a plan of a machine constructed in accordance with my invention. Fig. 2 is a side elevation. Fig. 25 3 is a vertical longitudinal section. Fig. 4 is a transverse section. Fig. 5 is a similar section in front of the drive-chain. Fig. 6 is a perspective of one of the scrapers.

Like numerals of reference indicate like 30 parts in all the figures of the drawings.

1 represents an oblong frame, consisting of opposite side bars 2, connected at their opposite ends by end bars 3. In the front end bar 3 is pivoted the front axle 4, having the 35 ground-wheels 5, and in the side bars 2 near their rear ends is the rear axle 6, having the ground-wheels 7, larger than the ground-wheels 5, and one of said ground-wheels 7 is provided with a sprocket-wheel 8 fast thereto. 40 At intervals the upper edges of the side bars 2 are provided with pairs of opposite boxes 9, and in each pair of boxes is mounted a transverse shaft 10, having a centrally-cranned portion 11, extending the entire width of the frame 1, and outside of one of said boxes each of the shafts is bent to form an operating lever or crank 12, which lever is disposed at a substantial right angle to the cranked portion 11, aforesaid. The side bar 2, at which 45 50 is located the levers 12, is provided with a shelf 13, and said levers when in a horizontal position lie thereupon.

Upon each of the crank-shafts 10, at their intermediate cranked portions, is suspended a U-shaped hanger 14, said hangers being 55 slotted or provided with openings at their upper ends for the loose passage therethrough of the shafts. Brackets 15 project from the opposite sides or terminals of the hangers near their lower portions, and in the ends of 60 the brackets are pivoted, as at 16, the opposite sides of the shovels or scrapers 17, so that said shovels or scrapers are free to tilt.

A pair of bars 18 depend from the side rails 2 near their front ends, and a similar pair of 65 bars 18 depend from said rails near their rear ends, and said bars are connected loosely by means of a chain 19, one arranged at each side of the machine. The front edges of the scrapers or shovels are sharpened, and the 70 side walls have connected therewith pairs of short chains 20, the opposite ends of the chains each being connected to the longitudinal chains 19, just mentioned.

Secured to the bars 2 at intervals are pairs 75 of standards 21, each pair being connected by a cross-bar 22, and upon said cross-bars is supported a pair of longitudinal bars 23, which at intervals, corresponding with the number and location of the shovels, have journaled 80 therebetween pulleys 24. The rear pair of bars 22 is extended beyond the standards 21 at that side of the machine at which is located the sprocket-wheel 8, and is connected by a cross-bar 26. In the bar 26 and the bar 23 is 85 journaled a shaft 27, carrying a sprocket 28, said sprocket having a toothed sleeve 29, which, together with the sprocket, is rigid with the shaft. At one side of the sleeve 29 there is loosely mounted upon the shaft a 90 drum 30, provided at its inner side with a toothed hub 31, adapted to engage the sleeve 29, and at its opposite side with a grooved brake-wheel 32. In the groove of the brake-wheel operates a lever 33, which is pivoted, 95 as at 34, to the rear bar 22. By means of this lever the toothed hub of the drum 30 may be thrown into and out of connection with the sleeve 29, and said lever may also be employed as a brake-lever. The sprocket 28 is 100 connected to the sprocket 8, by which it is driven, by means of a sprocket-chain 34. An endless rope or cable 35 is wound upon the drum 30 and over and under each of the pul-

leys 24, and in rear of each pulley short chains or cables 36 are connected to the chain or cable 35, and have their lower ends connected to the rear walls of the scrapers or shovels. 5 These short cables are slack, so as to permit of a raising and lowering of the shovels or scrapers into and out of contact with the ground without in any way interfering with such movements. At alternate sides of the 10 crank-shafts 10 are loosely pivoted push-bars 37, said latches extending to the rear and resting upon the next succeeding crank-shaft, as shown, and have their under sides at their rear ends shouldered or recessed, as at 38.

15 The operation of the invention is as follows: The machine being started, the first lever 12 is thrown to the rear, which lowers the first scraper of the series, and the edges of the same being obstructed by the ground tilts 20 the scraper to a proper position for scraping, the short draft-chains serving to limit the rearward swing of the scrapers or shovels. When the first shovel or scraper has become filled, the lever 12 is thrown to the front and 25 the push-bar pivoted thereto, the shoulder of which rests against the front portion of the shaft immediately in rear thereof, and serves to move said shaft to the rear beyond the vertical center of its bearing, whereby the second 30 shovel drops to the scraping position. In its movements the push-bar is guided by a guide-bracket 39, having a guide-slot in its upper end in which the latch reciprocates. When the second shovel has become filled, the operator throws the lever 12 thereof to the front, and the push-bar of said shaft serves in a 35 similar manner to lower the third shovel, and so on until the entire series of shovels are filled and raised. The machine is now driven to 40 the dumping-ground and the lever 33 shifted so as to throw the drum 31 into operative connection with the sleeve 29 of the sprocket 25. The drive-chain 34 operates the sprocket 35 and drum 31, which in turn moves the endless 45 chain or cable 36 and partially winds the short cables 36, and said cables tilt the rear ends of the shovels and dump their contents while the machine is in motion. The edges of the shovels coming in contact with the several 50 hills of dirt serve to level the same, as will be apparent. When the short cables 36 have been sufficiently tilted to accomplish the dumping, the lever 33 is shifted and the shovels automatically returned to a horizontal position, their rear ends being the heaviest by 55 reason of the point of pivot being in advance of the centers. When tilted for the purpose of dumping, the short ropes 36 are drawn partially over the drums 24 in front thereof, 60 so that when the lever 33 is returned and the rope 36 liberated the weight of the shovels is amply sufficient to return the ropes to their original positions.

From the above it will be apparent that I 65 have provided an exceedingly cheap and simple dirt-scraping machine, the capacity of which is equal to two or three ordinary ma-

chines, and yet requires but the same amount of horse-power. It will be seen that but one shovel is actually scraping at a time, and the 70 machine may therefore be drawn very readily by two horses, and the entire series of filled shovels may also be drawn by the two horses to the dumping-grounds. The capacity, therefore, of the machine is double that of the ordinary scraper, and without the proportionate increase in attendance and horse-power. It will be apparent that the number of shovels or scrapers may be indefinitely increased, 75 as desired. 80

Having thus described my invention, what I claim is—

1. In a road-scraper, the combination, with an oblong frame, of a series of shafts mounted therein and terminating at their outer ends 85 in operating-levers, a series of **U**-shaped hangers mounted upon the shafts upon centrally-cranked portions thereof, and a series of scraping-shovels supported in the lower ends of the hangers, substantially as specified. 90

2. In a road-scraper, the combination, with an oblong frame, of a series of shafts having centrally-cranked portions journaled in the frame and having their ends bent at a right angle to the cranked portion to form an operating-lever, a shelf or rest secured to one of the sides of the frame for the support of the levers, **U**-shaped suspension-hangers loosely mounted in the cranked portions of the shafts, and scraping-shovels secured in each of said 100 hangers, substantially as specified. 95

3. In a road-scraper, the combination, with an oblong frame provided at intervals with opposite pairs of bearings, of a series of shafts mounted in the bearings and having centrally-cranked portions and terminating at their outer ends in operating arms or levers, **U**-shaped hangers loosely suspended from the centrally-cranked portions and provided with forwardly-disposed brackets near their lower 105 ends, a series of scraping-shovels mounted in the brackets, draft-chains extending longitudinally along the sides of the shovels, depending standards for supporting the same, and a series of pairs of short chains connected 110 at their ends to the front ends of the shovels and at their opposite ends to the draft-chains, 115 substantially as specified. 120

4. In a road-scraper, the combination, with an oblong frame provided at intervals with bearings, of a series of shafts mounted in the bearings, cranked between their bearings, and provided with an operating-arm at one side of their bearings, **U**-shaped suspension-straps loosely mounted on the cranked portions, 125 scraping-shovels pivoted in the straps, and push-bars pivotally mounted upon each of the shafts and rearwardly-extending and loosely connected with the next succeeding shaft, substantially as specified. 130

5. In a road-scraper, the combination, with an oblong frame having a series of pairs of bearings, of a series of shafts mounted in the bearings and having centrally-cranked por-

- tions between the bearings and outside of the same, terminating in arms at substantially right angles to the cranked portions, guide-brackets located in rear of each of the shafts, 5 and push-bars provided with shoulders pivoted to each of said shafts and projecting in rear and taking against the next succeeding shaft and mounted in the brackets, substantially as specified.
- 10 6. In a road-scraping machine, the combination, with an oblong frame and a series of suspension-hangers provided with pivoted scraping-blades, of a series of pulleys mounted above and corresponding with the scraper or shovels, a drum, the shaft of the same, driving connections between the shaft and the ground-wheels of the machine, an endless belt or cable wound upon the drum and passing over and under each of the pulleys, a series of cables connecting the endless belt or cable with each of the shovels at their rear ends, and means for throwing the drum into and out of operative connection with the ground-wheel, substantially as specified.
- 15 7. In a road-scraping machine, the combination, with the oblong frame, the series of **U**-shaped suspension-hangers, and the scraping-shovels pivoted thereto, of the series of pulleys, an endless chain connecting the same and short chains connecting said chain to the shovels, 30 and means for operating said endless chain and simultaneously tilting the shovels, substantially as specified.
- 20 8. In a road-scraping machine, the combination, with the oblong frame, of the series of 35 crank-shafts, the **U**-shaped suspension-hangers provided at their front edges with brackets, and the shovels pivoted in the brackets in front of their centers, the standards 21, cross-bars 22, the rear two of which are extended beyond the standards, the connecting-bars 23 and 26, the axle 6, ground-wheels 7, one of which is provided with the sprocket-gear 8, the loose pulleys 24, arranged over the shovels in the side bars 23, the shaft 27, the 40 gear-wheel 28, the chain 34, connecting the gear-wheel with the sprocket-gear 8, the drum 30 for engaging the toothed sleeve 29 of the sprocket 28, and the grooved brake-pulley 32 and the lever 33 for shifting the same, substantially as specified.
- 25 In testimony that I claim the foregoing as my own I have hereto affixed my signature in presence of two witnesses.
